UNITED STATES PATENT OFFICE

2,626,226

PRINTED TRANSFER AND METHOD OF
USING SAME

James E. Adair, Chicago, Ill.

Application October 22, 1948, Serial No. 55,987

2 Claims. (Cl. 154—95)

1

The invention relates to transfers which are adapted to be applied to walls or surfaces and the production thereof.

One of the objects of the invention is to provide transfers of this type which are adapted for extended areas on walls or surfaces and can be produced at a sufficiently low cost to be usable as a substitute decoration in lieu of wall-paper.

Another object of the invention is to provide transfers of this type which are adapted to be applied to a wall or surface and removed therefrom.

Another object of the invention is to provide an improved method of producing printed transfers for application to walls or surfaces.

Other objects will appear from the detailed description.

These objects of the invention are attained primarily by printing with suitable ink and usually in colors, the design or matter, which is to be transferred to a wall or surface, on a backing of transparent wax-coated tissue-paper, and applying a coating of pressure-sensitive adhesive confined to, and coextensively with, the printed design or matter. The transparency of the backing renders the transfer visible while it is being applied to a wall or surface so that it can be correctly spotted or accurately placed on the wall. After the backing has been pressed against the wall or surface, the adhesive on the printed matter will adhere to the wall or surface and the backing can be freely peeled from the printed matter without marring or disturbing said matter. The use of a pressure-sensitive adhesive makes it possible to remove the transfer from the wall or surface without marring the wall or surface when a change in decoration is desired or when it is desired to substitute one decoration for another. The adhesive is applied only to the printed or decorated areas on the backing so that, when the transfer is pressed against the wall, no adhesive will be visible.

The invention consists in the several novel features hereinafter set forth and more particularly defined by the claims at the conclusion hereof.

The drawing illustrates, on a magnified scale, a section of a backing with a transfer embodying the invention.

In carrying out the invention, the design or matter of the transfer is printed with suitable ink, preferably of the type used for rotogravure printing and of the desired colors, upon one face of a web or sheet of a backing made of transparent paper coated with wax, such as

2

wax-coated tissue. This printing of the design or matter is done in reverse so that its front face will be on one wax-coated face of the backing. The printing may be advantageously done on a high speed rotogravure or other suitable press equipped with a sufficient number of cylinders to impress all of the colors on the backing and also apply a coating of adhesive to the printed portions on the web or sheet. For example, the portions of one color of the design or matter, for example black, are impressed on the backing by the first cylinder of the press; the portions of another color in the design or matter, for example blue, are impressed on the backing by the second cylinder; the portions of another color, for example red, are impressed on the backing by the third cylinder; the portions of another color, for example yellow, are impressed on the backing by the fourth cylinder; and films of white ink are impressed successively only on all the colored portions of the design or matter. The films last impressed on the portions forming the design or matter are applied so that any color on the wall to which the transfer is applied, will not show through the colored portions of the design or matter. The pressure-sensitive adhesive applied conforms with and is confined to the colored portions of the design or matter, so that when the transfer is applied to a wall or surface, no adhesive will be visible.

During the printing of the colors on the backing a limited degree of heat may be used to produce a slight penetration of the printing ink in the wax-coating of the backing. The colored portions of the design, being individually impressed on the backing, may be separated or disconnected to produce any desired design consisting of separated letters or portions, and no coating is necessary, such as lacquer heretofore used in decalcomania for preventing relative displacement of the portions of the design or matter while the transfer is being impressed on the wall.

In the drawing, the backing of wax-tissue is designated *a*; the colors of ink printed on the backing are collectively designated *b*; and the adhesive is designated *c*.

The pressure-sensitive adhesive coating which serves as an anchoring or sticking medium for holding the printed transfer against any surface to which it is applied, is usually composed of rubber, zinc oxide, adhesive resins and softeners, and fillers, is applied by the last roll of the

printing press to cover only the printed design or matter on the backing of wax-paper.

In applying the transfer to a wall, the backing is pressed against the wall, so that the adhesive will be applied to the wall. The transfer being visible through the transparent backing makes it possible to accurately spot or place the design in its correct position on the wall. Pressure is applied through the transfer to the printed matter and the adhesive, which will cause the pressure-sensitive adhesive to adhere to the wall and the printed matter to remain on the adhesive. The backing may then be readily peeled or pulled from the wall while the adhesive retains the printed design or matter on the wall. The adhesive affinity between the ink forming the portions of the design and the adhesive is greater in degree than the adhesive affinity of the ink for the wax-paper. As a result, when the backing of wax-paper is peeled off the wall, all portions of the transfer, whether connected or not will be secured on the wall in exact accordance with the printing on the backing. When the backing has been removed, only the printed matter or design of the transfer will be visible.

The completed product from the press may be wound into rolls for storage until it is to be used. In rolls, the pressure-sensitive adhesive will be removable from the contiguous face of the wax-coated backing, by unwinding the web from the roll for use, without delamination of the adhesive from the transfer, because the adhesive affinity between the transfer and the adhesive is greater than that between the adhesive and the wax coating on the contiguous convolution of the backing.

The product can be expeditiously produced on a high speed press including the printing of the colors and the application of the adhesive. This makes it possible to produce the transfers for decorating extensive areas, such as the walls of rooms, at a very low cost. The rolls may be dimensioned similar to wall-paper used for decorating the entire wall of a room, with transfers thereon for decorating extended or entire areas of the walls, so that the walls may be transferred-decorated without a residual backing in lieu of being covered with wall-paper which forms a backing for the decorations. The decorations on the wall may have the appearance of hand-painted murals.

When pressure-sensitive adhesive is used on transfers for decorating walls of rooms, the transfers may be readily removed for periodical substitution of different decorations or designs on the wall without marring the surfaces of the walls, because any remainder of the adhesive can be easily removed. This makes it possible to redecorate locations, such as reception rooms, powder rooms, restaurants or bars. It also makes

it possible where the decoration includes, in part, commercial advertising on walls, to periodically replace the transfer by different advertising matter.

5 The invention is not to be understood as limited to the details described, since these may be modified within the scope of the appended claims without departing from the spirit and scope of the invention.

10 Having thus described my invention, what I claim as new and desire to secure by Letters Patent is:

15 1. That improvement which comprises: ink-printing a transfer consisting of disconnected portions forming a design or composite matter on a substantially transparent wax-coated backing whereon the disconnected portions will be retained in fixed relation, the ink being separable from the backing, impressing a film of pressure-sensitive adhesive confined and conforming to the areas of the portions of the transfer, applying said areas of the adhesive to a support while the portions of the transfer are retained in fixed relation on the backing, and separating the backing 20 from the transfer while the transfer is adhesively retained on the support.

25 2. A product comprising a transparent wax-coated paper, a transfer of disconnected portions forming a design or composite matter, printed directly on and separable from the paper, and a film of pressure sensitive adhesive confined and conforming to the areas of the portions of the transfer, the adhesive being adapted to retain the portions of the transfer in fixed relation on a support, while the backing is separated from the transfer.
